US00D815652S

(12) **United States Design Patent** (10) Patent No.: **US D815,652 S**
Protzman et al. (45) Date of Patent: **** Apr. 17, 2018**

(54) **DISPLAY SCREEN OR PORTION THEREOF WITH GRAPHICAL USER INTERFACE**

- (71) Applicant: **Lutron Electronics Co., Inc.**,
Coopersburg, PA (US)
- (72) Inventors: **Brent Protzman**, Easton, PA (US);
Michelle L. Greene, Bethlehem, PA (US); **Erica L. Clymer**, Northampton, PA (US); **Jennifer Wong**, Briensburg, PA (US); **Samuel F. Chambers**, Gwynedd Valley, PA (US); **Laura Marie Friedlander**, Harleysville, PA (US); **Edward J. Blair**, Telford, PA (US); **Stephen Lundy**, Coopersburg, PA (US); **John N. Callen**, Center Valley, PA (US)
- (73) Assignee: **Lutron Electronics Co., Inc.**,
Coopersburg, PA (US)
- (**) Term: **15 Years**
- (21) Appl. No.: **29/583,411**
- (22) Filed: **Nov. 4, 2016**

Related U.S. Application Data

CLAIM

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof and form no part of the claimed design.
